UNITED STATES PATENT OFFICE

95,797

DESIGN FOR A DISPLAY STAND FOR HOSIERY OR THE LIKE

Emil J. Berger, Hatfield, Pa., assignor to Dexdale
Hosiery Mills, Lansdale, Pa., a corporation of Pennsylvania

Application October 26, 1934, Serial No. 53,768

Term of patent 14 years

To all whom it may concern:

Be it known that I, Emil J. Berger, a citizen of the United States, residing at Hatfield, in the county of Montgomery and State of Pennsylvania, have invented a new, original, and ornamental Design for a Display Stand for Hosiery or the like, of which the following is a specification, reference being had to the accompanying drawing, forming part thereof.

In the drawing:

Fig. I is a perspective view of a display stand for hosiery or the like embodying my new design.

Fig. II is a fragmentary view showing the lower part of the stand in vertical elevation.

I claim:

The ornamental design for a display stand for hosiery or the like, as shown and described.

EMIL J. BERGER.
